BAR OF SOAP OR SIMILAR ARTICLE

Livingston C. Douglas, Leonia, N.J., assignor to Colgate-Palmolive Company, New York, N.Y., a corporation of Delaware

Filed Sept. 26, 1966, Ser. No. 4,014

Term of patent 14 years

(Cl. D73—1)

FIG. 1

FIG. 4

FIG. 2

FIG. 5

FIG. 3

FIG. 6

FIG. 1 is a perspective view of a bar of soap or similar article showing my new design;

FIG. 2 is a plan view thereof;

FIG. 3 is a side elevational view thereof, showing the side not visible in FIG. 1;

FIG. 4 is an end elevational view thereof, showing the end not visible in FIG. 1;

FIG. 5 is a cross-sectional view taken on the line 5—5 of FIG. 2; and

FIG. 6 is a cross-sectional view taken on the line 6—6 of FIG. 2.

I claim:

The ornamental design for a bar of soap or similar article, as shown and described.
